DESIGN FOR A DOLL OR SIMILAR ARTICLE

Susanne Willa, New York, N. Y.

Application July 9, 1938, Serial No. 78,373

Term of patent 3½ years

To all whom it may concern:

Be it known that I, Susanne Willa, a citizen of the United States, residing at 405 East 54th Street, Manhattan, in the county of New York and State of New York, have invented a new, original, and ornamental Design for a Doll or Similar Article, of which the following is a specification, reference being had to the accompanying drawing, forming part thereof.

I claim:

The ornamental design for a doll or similar article, substantially as shown.

SUSANNE WILLA.
